[57] **CLAIM**

The ornamental design for a brush clock, as shown and described.

DESCRIPTION

FIG. 1 is a front elevational view of a brush clock showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a perspective view thereof; and,

FIG. 8 is a front, left side, and bottom perspective view thereof with the brush portion exposed, the rear and right side of FIG. 8 being identical to the front and left side shown.
